US0D1095712S

(12) United States Design Patent (10) Patent No.: US D1,095,712 S
(45) Date of Patent:  Sep. 30, 2025

(54) RACQUET FOR GAMES

(71) Applicant: Evosport AB, Piteå (SE)

(72) Inventor: Joacim Bergström, Piteå (SE)

(73) Assignee: Evosport AB, Piteå (SE)

() Term: 15 Years

(21) Appl. No.: 29/909,696

(22) Filed: Aug. 9, 2023

Related U.S. Application Data

(63) Continuation of application No. 29/816,641, filed on Nov. 23, 2021, now Pat. No. Des. 999,307.

(30) Foreign Application Priority Data
